US00D763193S

(12) **United States Design Patent**
Tyler et al.

(10) **Patent No.:** **US D763,193 S**
(45) **Date of Patent:** **** Aug. 9, 2016**

(54) **BUS BAR CARRIER FOR LITHIUM ION BATTERY MODULE**

(71) Applicant: **Johnson Controls Technology Company**, Holland, MI (US)

(72) Inventors: **Matthew R. Tyler**, Brown Deer, WI (US); **Christopher M. Bonin**, South Milwaukee, WI (US); **Richard M. DeKeuster**, Racine, WI (US); **Dale B. Trester**, Milwaukee, WI (US)

(73) Assignee: **Johnson Controls Technology Controls**, Holland, MI (US)

(**) Term: **15 Years**

(21) Appl. No.: **29/528,996**

(22) Filed: **Jun. 2, 2015**

(51) LOC (10) Cl. **13-02**

(52) U.S. Cl.

USPC **D13/119**

(57) **CLAIM**

The ornamental design for a bus bar carrier for a lithium ion battery module, as shown and described.

DESCRIPTION

FIG. 1 is a top perspective view of a bus bar carrier for a lithium ion battery, showing our new design;
FIG. 2 is a front top perspective view thereof;
FIG. 3 is a rear top perspective view thereof;
FIG. 4 is a front bottom perspective view thereof;
FIG. 5 is a rear bottom perspective view thereof;
FIG. 6 is a rear elevational view thereof;
FIG. 7 is a front elevational view thereof;
FIG. 8 is a top plan view thereof;
FIG. 9 is a bottom plan view thereof;
FIG. 10 is a right side elevational view thereof; and,
FIG. 11 is a left side elevational view thereof.

1 Claim, 6 Drawing Sheets
